CLAIM

The ornamental design for a blot and gel imaging instrument display screen with graphical user interface, as shown and described.

DESCRIPTION

FIG. 1 is a view of a first embodiment of a blot and gel imaging instrument display screen with graphical user interface of our new design; and,
FIG. 2 is a view of a second embodiment of a blot and gel imaging instrument display screen with graphical user interface of our new design.

The broken lines showing the display screen and elements of the graphical user interface form no part of the claimed design.

1 Claim, 2 Drawing Sheets

FIG. 1

FIG. 2
